UNITED STATES PATENT OFFICE.

CHARLES H. HAESELER, OF PHILADELPHIA, PENNSYLVANIA.

ROCK-DRILL.

1,214,542.

Specification of Letters Patent. Patented Feb. 6, 1917.

Application filed February 24, 1916. Serial No. 80,109.

To all whom it may concern:

Be it known that I, CHARLES H. HAESELER, a citizen of the United States, residing in the city of Philadelphia, county of Philadelphia, and State of Pennsylvania, have invented certain Improvements in Rock-Drills, of which the following is a specification.

My invention is a rock drill of peculiar construction designed to provide simplicity, 10 strength, durability, efficiency and flexibility in operation.

My invention is characterized by improved means for intermittently delivering water to and through a hollow drill steel to 15 its cutting face (to cool the cutting point, allay the dust, and remove cuttings from the bottom of the hole); for connecting the steels or cutting tools with the percussive mechanism; and for controlling the exhaust 20 ports to regulate the action of the percussive mechanism and supplement the action of the water in removing cuttings or detritus that may have accumulated in the hole being drilled.

25 A desideratum attained by my invention is the intermittent supply, at predetermined intervals, and the delivery through the drill steels of the amount of water desired for allaying the dust and washing out the cut- 30 tings, with efficient results and saving in water.

35 A further desideratum is attained by the peculiar means devised for connecting the drill steels so that they are held in their desired relation and are removable without difficulty when this is desired.

40 A further desideratum results from the special means for controlling the live air and providing additional means for blowing out the detritus from the hole cut by the drill steel.

45 The nature and advantages of my improvements will be fully understood by reference to the following description and the accompanying drawings of a preferred embodiment thereof.

50 In the drawings, Figure 1 is a longitudinal sectional view of a form of the construction selected for illustrating the improvements; Fig. 2 is a part sectional elevation of the same construction viewed at right angles to the position shown in Fig. 1; Fig. 3 is an

enlarged longitudinal sectional view taken through the lower part of the mechanism; Fig. 4 is a sectional view taken on the line 55 4—4 of Fig. 3; Fig. 5 is a sectional view taken on the line 5—5 of Fig. 3; Fig. 6 is a sectional view taken on the line 6—6 of Fig. 3; Fig. 7 is a side elevation of the mechanism, illustrating the exterior construction of the means for supplying water and regulating the air; Fig. 8 is a sectional view taken on the lines 8—8 of Figs. 3 and 7; Fig. 9 is an enlarged detailed view of the improved means for controlling the air in 65 one position of said means; and Fig. 10 shows a second position of the mechanism illustrated in Fig. 9.

The drill, in the form thereof illustrated in the drawing, comprises the casing 1 containing the aligned cylinders 2, 3, and 4. A piston 5 acts in the cylinder 2 and has fixed thereto a reduced section or hammer 6 which acts in the cylinder 3. A stock 7 is provided with the cylindrical section 8 which 75 acts in the cylinder 4, and with an angular, as a hexagonal, section 9 on the end of the section 8, the section 9 acting in a corresponding bearing 10. The stock 7 is provided with a socket 11 adapted for receiving 80 the conforming end of the drill steel 12, with suitably spaced apertures 13 adapted for the reception of the radially movable tapered gibs 14 designed to grip the steel, and with a male screw thread 15 adapted for engaging 85 a female screw thread 16 of a revoluble sleeve 17, the latter having a tapered or conical inner surface 18 adapted for engaging the inclined exterior surfaces of the gibs in wedging relation so as to cause them to grip the steel securely. The threads 15 and 16 are preferably formed so as to provide limited play between them longitudinally of the drill, the grooves between the teeth being enlarged to permit this limited free action. 95

In drill chucks heretofore constructed having a tapered sleeve engaging a corresponding taper of the gibs for holding the drill steel, it frequently happens that the jar resulting from the operation of the drill 100 will cause the sleeve to creep farther on the taper and bind so tightly on the gibs that it cannot be released.

By the arrangement above described, the

sleeve 17 may be drawn up by means of the screw threads so as to cause the gibs to grip the steel, and upon the operation of the machine a further longitudinal movement of the sleeve is permitted, resulting from the jar of the hammer blows, so that it more tightly grips the gibs, such additional longitudinal movement of the sleeve being limited however by the engagement of the lower faces of the chuck threads with the upper faces of the sleeve threads, whereby jamming is avoided and the sleeve may be readily backed off or released by means of a wrench or hammer blow on the lugs.

15 The stock 7 is provided with an axial passage 19 extending from the socket 11 through the parts 8 and 9, and the steel 12 (with its cylindrical contour terminating in a rounded end conforming to the like socket 11) is provided with the axial passage 20 in alignment with the passage 19. A small port or passage 21 extends from a point in a flat face of the section 9 into the passage 19, the port being constantly in the cylinder or cylindrical sleeve 4 and in communication with a port 22 of said cylinder. The port 22 is connected intermittently with a passage 23 which communicates with a passage 24 in a hub 25 on the casing. The hub 25 has a water conduit 26 fixed thereto, in communication with the passage 24, by a sleeve 27. The sleeve 27 and a plug 28, for closing the end of the passage, are locked by plungers 29 and 30 held in engagement therewith by a spring 31.

The cylinder or cylindrical sleeve 4 is revolvable in the lower end of the casing 1 by fixing to its upper end a toothed barrel 32 which meshes with a driving pinion 33 fixed on a journal shaft 34, the shaft being driven by providing it with a worm wheel 35 and engaging such wheel by a worm 36 fixed to and driven by the rotary motor 37. It will be understood that this motor, acting through the intermediate mechanism, revolves the cylindrical sleeve 4 and, through its engagement with the hexagonal section 9, the stock 7 and steel 12 constantly, causing the port 22 to register intermittently with the passage 23 and to be closed by the casing 1 at other times. This effects the admission of water through the port 21 and passages 19 and 20 intermittently, the periodic admission of water effecting the work of allaying the dust and washing out the drilled hole more efficiently with less water than where it is constantly admitted.

60 The hammer or piston section 6 contains an axial passage 38 connected by the branch passages 38' with the cylinder and in alignment with the passage 19.

65 A passage 39 in the wall of the case is in constant communication with the forward end of the cylinder 2 and the passages 38'. A passage or port 40 is adapted for com-

munication with the cylinder 2 and the passages 38', in the rearward position of the piston 5. A passage 41 is adapted for communication with the cylinder 2 in the forward position of the piston 5. The passage 39 communicates with a valve-chamber 42 under control of a valve 43 containing ports 44 and 45, the ports 40 and 41 being in constant communication with such chamber.

70 A bayonet joint, provided by the angular slot 46 and the studs 46', serves to control the movement of the valve 43.

75 The motive fluid is admitted to the cylinder 2 and operates the piston 5 in a manner analogous to that described in my Patent No. 1146870, flowing through the passages 47, 48, 49, 50, 51, and 52, incidentally operating the rotary motor 37 and acting under control of the check valve 53.

80 In the position of the mechanism illustrated in Figs. 1 and 9, there is free communication between the cylinder spaces at the opposite ends of the piston 5 through the passages 39, 44, 42, and 41, without loss of air to the atmosphere excepting through the passages 38', 38, 19 and 20, whereby special means are provided for blowing the detritus out of the hole made by the drill. In the position of the valve or bonnet 43 illustrated in Fig. 10, the passage 39 is closed, the passages 40 and 41 are in communication with the atmosphere through the now open ports 45 and air escapes from the cylinder 2 to the atmosphere when the piston 5 is in position for establishing communication between such cylinder and the respective ports 40 and 41.

85 Having described my invention, I claim:

1. In a rock drill, the combination of a stock having a longitudinal socket, transverse ways and a male thread, with a steel having an end in said socket, gibs movable in said ways to clamp said steel, and a sleeve having an inner surface engaging said gibs in wedging relation and a female thread engaging said male thread in loose relation so as to permit a limited lateral movement between said threads.

100 2. In a rock drill, having a case and a percussive tool adapted to reciprocate in said case, a stock connected with said case so as to be movable relatively thereto by said tool, said stock having a thread, a drill steel, and means connecting said stock with said case and fixing said steel to said stock, said means comprising a thread loosely engaging said thread first named so as to provide limited lateral movement between said threads.

105 3. In a rock drill, having a case and a percussive tool adapted to reciprocate in said case, a stock connected with said case so as to be movable relatively thereto by said tool, said stock having a screw thread,

a drill steel, and means for loosely coupling said stock to said case and fixing said steel to said stock, said means comprising a screw thread loosely engaging said thread first 5 named so as to provide limited lateral movement between said threads, whereby said means are operated by the blow of the tool

to tighten without jamming the grip on said steel.

In testimony whereof, I have hereunto 10 set my name this 23rd day of February, 1916.

CHARLES H. HAESELER.
